UNITED STATES PATENT OFFICE.

ROBERT STOWE ROBSON, OF CAMBRIDGEPORT, MASSACHUSETTS.

MACHINE FOR CUTTING PRINTERS' RULES.

SPECIFICATION forming part of Letters Patent No. 271,204, dated January 23, 1883.

Application filed December 18, 1882. (No model.)

To all whom it may concern:

Be it known that I, ROBERT STOWE ROBSON, of Cambridgeport, in the county of Middlesex, of the Commonwealth of Massachusetts, have invented a new and useful Improvement in Machines for Cutting Printers' Rules; and I do hereby declare the same to be described in the following specification and represented in accompanying drawings, of which—
10 Figure 1 is a top view, Fig. 2 a front end elevation, Fig. 3 a rear end elevation, and Fig. 4 a side view, of a machine embracing my invention, the nature of which is defined in the claims hereinafter presented. Fig. 5 is a transverse section, and Fig. 6 a longitudinal section taken through the movable bed and its adjustable clamp-gage. Fig. 7 is a front view of the movable knife.

In the said drawings, A denotes a standard or frame for supporting the main operative parts of the machine. Within this frame, and adapted to it so as to move vertically in it, is a cutting-knife carrier, B, which has fixed to it a knife, C, whose lower edge is its cutting-edge, and is made obtuse angular, as shown. There is pivoted to the frame or standard A a cam-lever, D, whose cam *a* bears on the top of the knife-carrier. The shorter arm of the lever is flat, and projects down from the lever in front of the knife-carrier, and there is in such arm a curved slot, *c*, through which a stud, *d*, from the knife-carrier projects. Furthermore, there is applied to the lever and the frame A a spring, *e*, for turning the lever so as to force its longer arm upward, and thereby, by means of the slot *c* and stud *d*, cause the knife-carrier to rise relatively to a stationary rest or bar, *f*, arranged in the stand. In front of this rest or bar *f* there is what I term the "adjustable bed" E, which is a flat arm pivoted at or near its inner end to the frame or standard A. From the arm, and concentric with one of its pivots, there projects downward a semicircular extension, F, provided with a curved slot, *h*, to receive a clamp-screw, G, which, arranged in the slot, screws into the stand A. A semicircular and divided limb, H, projects upward from the part F against an index-pointer, I, attached to the frame A. 50 This limb H and pointer I serve to indicate the

angle of inclination of the bed E, the clamp-screw and slotted extension answering to fix the bed in any angular position within the range of its motion. For convenience of holding the bed raised at different altitudes, I provide the extension at its periphery with teeth *k* and the frame A with a weighted catch-lever, *l*, to act with such teeth.

Arranged lengthwise on the adjustable bed E is a clamp-bar, K, having projecting from the middle of its lower side and extending from one to the other end thereof a straight tongue, *m*, which enters a corresponding groove, *n*, made lengthwise in the bed E. The bar K at its inner end is beveled at an angle of forty-five degrees, and there are in the bar, longitudinally thereof and extending down through the tongue *m*, two slots, *p p*, to receive clamp-screws *o o*, which go through the slots and screw into the bed E. In the groove *n* is a bow-spring, *q*, for forcing the bar K upward. Furthermore, there is marked lengthwise on the adjustable bed E, parallel with the clamp-bar, a scale, *s*, of inches and parts of inches, and there projects from the said bed a stop, *t*, which, by bringing up against the rest or bar *f*, causes the upper face of the bed E to stand at a right angle to the outer face of the said bar *f*. An arm, L, pivoted to a bracket, *u*, fixed to the bed E at its outer end, supports a gage-rod, M, that slides freely through the arm, and may be sustained in position by a clamp-screw, *v*, screwed into the arm. This arm can be turned so as to carry the gage-rod M down upon the bed E and upon either side of the clamp-bar K. The rod M serves as a gage or stop for a rule to abut against in order to determine where it is to be severed, it preparatory to being cut being inserted between the rest and the knife and up to the inner end of the gage, and being subsequently held firmly in place on the bed E by means of the clamp-bar K and its screws, the rule extending under the said clamp-bar. The movable knife has two straight cutting-edges, *y y'*, making an obtuse angle with each other, such being to admit of a rule being cut with a drawing or shear stroke of the knife from whichever edge of the clamp-bar K the rule may extend.

Through the frame A there is a hole, *w*, for

reception of the gage-rod M, there being screwed into the frame a clamp-screw, x, to clamp the rod in the hole. The rod is shown by dotted lines as arranged in the hole, instead of in the 5 arm L, in order for the part y of the rod to serve as a stop for a rule to bring up against, preparatory to being cut, in case of the rule being introduced between the knife and rest from the front side of the frame.

10 With the machine above described a rule may be cut either "square" or "mitering" or at any desirable angle to one of its parallel sides, and it may be divided into pieces of equal lengths, as occasion may require, it, preparatory to each 15 cutting of it, being properly introduced between the rest and knife, and the latter being subsequently forced downward so as to sever the rule supported by the rest.

I claim—

20 1. In combination with the frame or standard A and the rule-rest f thereof, and with the cutting-knife C, as described, having mechanism for elevating and depressing it, (the said

knife,) as explained, relatively to the said rest, the adjustable bed E, pivoted to the said standard or frame A, and provided with the movable clamp-bar K and its screws, and with means of supporting such bed in a horizontal position as well as in any inclined position within the range of its movement, all being substantially 25 30 as set forth.

2. The combination of the index-pointer projecting from the standard with the described limb of the adjustable bed, and with such standard and bed, provided with cutting and 35 clamping devices, substantially as set forth.

3. The combination of the pivoted arm L and its gage-rod M with the adjustable bed E, the frame or standard A, and its rule-rest f, and with the cutting-knife C, provided with 40 means of operating it, as described.

ROBERT STOWE ROBSON.
